UNITED STATES PATENT OFFICE.

EDWIN H. BENNERS, OF ELIZABETH, NEW JERSEY.

METHOD OF PRODUCING PAVING-BLOCKS.

1,239,762.

Specification of Letters Patent. Patented Sept. 11, 1917.

Application filed January 31, 1914. Serial No. 815,607.

To all whom it may concern:

Be it known that I, EDWIN H. BENNERS, a citizen of the United States, residing at Elizabeth, county of Union, and State of New Jersey, have invented a certain new and useful Method of Producing Paving-Blocks, of which the following is a specification.

This invention is a process of producing paving blocks, an essential feature of which block is a body portion composed of a molded concrete mass, the latter being bound at the wearing surface of the block with a metallic reinforcement. 10
In my present invention the body of the block is composed of concrete, usually cement, sand and a mineral aggregate of one kind or another, the same being molded to the desired form and size, whereby the sand and cement in a semi-liquid condition serves 20 as a grout in binding the mineral aggregate into a solid, compact and homogeneous mass. The concrete mixture constitutes practically an artificial stone wherein the steel reinforcement is so embedded and combined as to become an inseparable and indivisible part of the paving block structure. Such artificial stone or concrete mixture resists the effects of surface traffic to as good, 25 or even better advantage, than an asphaltic block, the steel reinforcement being of such a form and so positioned as to produce a surface of such nature that the concrete resists the tendency under street traffic to 30 "chip out" of the block.

A distinctly novel feature of the invention resides in the molding of the block in a manner to secure an accumulation of the coarse mineral aggregates at the wearing 40 surface of the block. This is obtained by molding the block "face downward", for which purpose the steel reinforcing band is deposited upon the bottom part of the collapsible steel or other mold, after which the 45 concrete mixture, previously prepared so that the cement and sand is relatively thin or of creamy consistency to serve as a grout, is poured into the mold, whereupon the coarse and heavy pieces of the mineral aggregate settle by gravity to the bottom part 50 of the mold, and thus the grout of cement

and sand is free to flow into the interspaces between the mineral aggregate for the purpose of obtaining a bond which not only unites the concrete mass into a homogeneous body but operates as a binder between the 55 surface steel reinforcement and the concrete. As a result, the block, when removed from the mold and turned up to assume a normal position, is characterized by a solid 60 surface composed of the steel band and an accumulation of the coarse large pieces of stone all bound up into a solid whole, the mineral aggregate being thus disposed at or in the surface of the block where its wear 65 resisting qualities are most desired and are made most available.

In the drawings,

Figure 1 is a plan view of a reinforced concrete paving block embodying this invention.

Fig. 2 is a vertical cross section on the line 2-2 of Fig. 1.

Fig. 3 is a view in end elevation of the paving block looking toward the left of Fig. 1.

Fig. 4 is a vertical section illustrating the method of molding the paving block face down or in an inverted position.

Figs. 5 and 6 are detail views in cross 80 section through different forms of the steel reinforcement.

Fig. 7 is a plan view of a portion of a roadway paved with concrete blocks in accordance with this invention.

Fig. 8 is a cross section through the roadway paved with reinforced concrete blocks of this invention.

Fig. 9 is a plan view of a portion of a roadway and a street car track paved with 90 reinforced concrete blocks of this invention.

The reinforced concrete block of my invention is illustrated more particularly in Figs. 1, 2 and 3 of the drawings. The body A of the block consists of a homogeneous 95 mass of concrete, and this block is provided with a metal reinforcement B in the form of a band which constitutes a part of the wearing surface of the block. The concrete body is composed of Portland cement 1 part, sand 2 parts, and a suitable mineral aggregate 4 parts, although the particular ingre-

dients and the proportions may be modified or varied as found necessary or desirable. The mineral aggregate may be trap rock, gravel or slag, but, obviously, the particular 5 aggregate employed will depend somewhat upon conditions.

The reinforcement B is a skeleton frame, preferably composed of steel and having the form shown more particularly in Figs. 1, 10 2, 3, 5 and 6. The steel reinforcement is substantially rectangular in shape consisting of side bars b, an end bar b', and a divided bar c. The end portions of the metal band are extended inwardly thereof 15 so as to produce a long member d and a short member d'. The long member d extends for practically the length of the reinforcing band, and is positioned substantially centrally thereof, whereas the short member 20 d' extends into the material of the concrete body for a suitable distance parallel to the long member d, it being preferred to give an abrupt bend d² to the free end of the short member in order that the same may 25 have a firm anchorage in the concrete material. The divided end c of the metal reinforcement provides for the necessary expansion and contraction of the metal so as to make it responsive to changes in the 30 temperature or weather conditions, whereas the arrangement of the members d, d' within the block divides the surface of the block so as to interrupt the continuity of the concrete surface and produce relatively thin lengths 35 or strips of metal in alternate relation to the sections of concrete.

The metal band embraces the marginal portions of the block so as to confine the concrete material at the wearing surface of 40 said block, and said metal band is practically embedded in the concrete material of the block, and, furthermore, it is positioned at the wearing surface thereof so that the wearing surface is composed in part of concrete 45 material and of steel.

My invention is characterized by a novel mode of molding the concrete block so as to secure an accumulation of the rough mineral aggregate at the surface of the block where 50 it is most desired or required, said method of molding being illustrated in Fig. 4. According to this invention the block is molded in an inverted position and in molds of suitable construction, it being preferred to deposit the materials in collapsible steel molds represented diagrammatically at C in Fig. 4. The metal band B is deposited within the mold so as to rest upon the bottom thereof, and thereafter the plastic concrete material 55 is poured into the mold. The concrete material is prepared by mixing together the ingredients heretofore specified, a proper quantity of water being added to produce a grout of the sand and cement, the grout being of a semi-liquid or creamy consistency.

Now when the concrete material is introduced into the mold and in contact with the metal band B therein the mixture is allowed to settle, and as the heavy pieces of coarse material composing the mineral aggregate 70 will accumulate at the bottom of the mold, the grout of sand and cement acting as a bond in order to bind the mineral aggregate and the metal reinforcement into a homogeneous mass, thereby securing a permanent 75 union between the metal and the concrete materials. The concrete mixture is allowed to rest for a proper length of time in order that the mixture may become sufficiently dry and secure the union of the several ingredients, after which the block is removed 80 from the mold and set aside for a proper length of time so as to "season" it.

It is preferred to construct the metal reinforcement substantially as shown in Figs. 85 5 and 6 in order that said reinforcement may be anchored firmly in the concrete material within which the reinforcement is partially embedded. As shown in Fig. 5, each part of the metal strip or band may be provided with inwardly extending ribs or flanges having the form shown at e or e', but, again, the metal band may be provided at its lower edge with an inwardly extending hoop-shaped lip, indicated at e² in Fig. 90 6. It is apparent that the inwardly extending lip of the band of whatever form shown will become embedded in the concrete material so as to form a firm anchorage of the reinforcement to the block.

It may be, and preferably is, desirable to water-proof the blocks, and the invention makes provision for securing this condition. After the blocks are thoroughly dried or 100 seasoned, they are made water-proof by the 105 addition of an oleaginous substance thereto, which substance can be in the form of a hot wax solution. The seasoned blocks are immersed in this wax solution for a suitable length of time, and owing to the more or 110 less porous nature of the concrete mixture, the water repellent agent is absorbed into the concrete material so that the surface of the block is saturated for a suitable depth with said moisture repellent agent. Obviously, the block may be treated with the moisture repellent agent on the wearing surface only thereof, but it is apparent, furthermore, that this agent may be applied to the sides, ends and bottom surface of 115 120 the molded block.

In Figs. 7 and 8 of the drawings there is shown a roadway paved with the reinforced concrete blocks of this invention, from which it appears that the blocks are laid in end 125 to end relation and in rows, the blocks extending in the direction of their length across the roadway. Of course, the blocks should be laid as closely as possible, the expansion and contraction of said blocks due 130

to temperature changes being taken up by an asphaltic cement filler E. This filler is about an inch in width along each curbing, and it performs three several purposes; first, 5 it serves as a water-proof joint between the paving blocks and the curbing, for the purpose of precluding water from flowing through the sand base upon which the blocks are laid; second, it takes up unevenness in the 10 ends of the rows of blocks, due to various causes, and, third, it constitutes an expansion joint so as to provide a means for getting at any single row of blocks for the purpose of removing the same without breaking 15 any of the blocks, it being possible to always replace the blocks exactly as originally laid. It is apparent that the cement filler can easily be removed with an ordinary pick, and, further, that any block can be separated 20 from the joining ones by the operation of a pick.

The rows of blocks are positioned on a leveled or rolled sand base F, the latter being imposed upon a foundation G of concrete. 25 When the blocks are laid, an opening of about one-quarter ($\frac{1}{4}$) of an inch should be left between the rows, and subsequent to the laying of the blocks sand is swept over the surface of the pavement. 30 The loose sand fills the spaces between the rows of blocks and the crevices between the blocks in the rows, after which a liquid grouting of cement is flooded over the surface of the pavement so that the grout will 35 run down through the sand filler, thus producing a concrete filling between the blocks and forming practically a monolithic pavement.

At street crossings and at one or more 40 points in a city block the pavement should be laid by installing an inch plank between the rows of blocks, and after the pavement is laid the plank is removed, this space and the curb joints are filled with asphaltic 45 cement to serve as longitudinal expansion joints. By having an expansion joint on all four sides at street crossings it is possible to remove the joint when it is desired to obtain access to sewer and underground 50 structures at the street crossing, experience having shown that it is necessary to make repairs and alterations at such crossings more frequently than at other places.

A pavement laid in accordance with this 55 invention is characterized by well-defined lines of cleavage on all four sides of every block, thereby making it possible to remove any broken or defective blocks or to open up any particular spot in the surface with 60 little labor and no destruction of material, and, also, to replace the street surfaces, so that the replaced surface will be homogeneous with its surroundings and identical with it in surface and wearing qualities.

This is not the case with sheet asphalt, 65 Belgian block, or any other road surface with which I am familiar, except a pavement made of asphalt block having steel reinforcing as in my prior patent.

In Fig. 9 of the drawings there is shown 70 a roadway wherein the tracks of a tramway are laid with my reinforced concrete blocks. The space between the curbing H and the rails H' of the tramway is filled with the blocks laid in end to end order and in rows, 75 and these blocks also fill the spaces between the tram rails H' and the slot rails H² of the underground railway. In thus installing the paving blocks between the rails and the curbing it is recommended that the asphalt 80 filler be used in place of sand, for the reason that the expansion and contraction of the blocks and their metal reinforce is comparatively small owing to short lengths of steel. The employment of the asphalt filler not 85 only compensates for all expansion and contraction, but will act to deaden the sound and relieve any tendency to "pinch" the slot, i. e. exert undue pressure thereon, in addition to which advantage it is apparent that 90 any block or row of blocks between the rails can be removed and relaid within a very short time and at minimum cost for labor and material.

While I have particularly shown and described the blocks as adapted for paving purposes, it will be understood that the reinforced concrete block of my invention may, also, be used for various other purposes, such as lining for reservoirs, underground construction, footings for foundation or concrete tanks, etc. The waterproofed blocks for reinforced monolithic construction in units to fit unusual shapes fills a long-felt want in the engineering and 105 industrial arts.

Having thus fully described the invention, what I claim as new, and desire to secure by Letters Patent is:

1. The method of producing a reinforced concrete paving block which consists in positioning a metal band upon the bottom portion of a mold, depositing a concrete mixture including a mineral aggregate and a grout within the mold and into contact with said metal band, whereby the mineral aggregate will stratify at the surface of the block and adjacent the metal band, and uniting the concrete and the metal band into a homogeneous mass by the bonding action 110 of the grout entering into the concrete mixture.

2. The process of producing a reinforced concrete paving block which consists in positioning a metal band within a suitable mold, preparing a concrete mixture including a mineral aggregate and a semi-liquid grout of sand and cement, depositing said 120

concrete mixture within the mold and into contact with the metal band, allowing the mineral aggregate to accumulate by gravity thereof into a strata or layer at the bottom of the mold and next to the metal band, and bonding the whole into a homogeneous mass by the action of the semi-liquid grout.

In testimony whereof I have signed my name to this specification in the presence of two subscribing witnesses.

EDWIN H. BENNERS.
